FUSE PLUG

Louis Ludwig, Brooklyn, N. Y.

Application May 25, 1935, Serial No. 23,465

2 Claims. (Cl. 200—130)

The invention relates to electrical fuse plugs and to the manufacture of electrical fuse plugs, and more particularly to a method for securing the metal screw-shells on such fuse plugs. The 5 invention has for its main object to provide a new and novel manner in which to rigidly secure the metal screw-shell to the fuse plug, so as to effectively prevent it from turning or becoming loose. Another object is to provide a method 10 which will greatly reduce the cost of the moulds employed, as well as the moulded parts used in such appliances, and which will in general reduce the cost of manufacturing and assembling the 15 appliances. Another object is the provision of an improved electrical fuse plug in which a substantial arcuate solder extension from a substantial solder body both assures an electrical circuit and is effective in practice to secure the threaded shell on a cylindrical body member against removal therefrom.

These and various other objects and advantages will be readily understood from the following description and from the accompanying drawing of a preferred embodiment of the invention, in 25 which, however, modifications may be made without departing from the scope of the appended claims. In the drawing

Fig. 1 is a cross-sectional, side elevation of a fuse plug to which the invention has been applied;

Fig. 2 is a front elevation of same with a part of the screw shell broken away;

Fig. 3 is a top view, shown with the customary mica disc and metal rim removed;

Fig. 4 is a cross-sectional top view, taken on line 4—4 in Fig. 2; and

Fig. 5 is a side elevation of the solder construction employed for holding the metal shell in place.

While the drawing illustrates and the specification describes a fuse plug, it will be understood that this invention may be applied to other electrical appliances on which a screw shell is employed in a similar manner to which it is employed on a fuse plug.

The ordinary fuse plug may be made of porcelain, glass, "Bakelite", or some other plastic material, and to assure that the screw shell is firmly secured to the body member, a thread is moulded on the lower end of the body member. The moulding of this thread adds considerably to the expense of manufacturing the body member, particularly when the body member is made of "Bakelite" or like materials. Such materials require the use of so-called split moulds, as the

thread prevents the withdrawal of the body member from a solid mould.

In the present invention the thread may be dispensed with entirely so that the body member has an external cylindrical wall and may be manufactured at a much lower cost than was formerly possible, and made in moulds of much simpler and cheaper construction.

Reference is now had to the drawing in which the body member of a fuse plug is shown at 10, 10 the screw shell at 11, the center contact at 12, the interior recess at 13 and the fusible metal link at 14. The fuse illustrated is made of "Bakelite" and the whole body member 10 is formed in one piece and provided with the customary transparent mica disc 15 and metal ring 16 for securing the mica disc in the recess 17. The lower part 18 of the body member is moulded without the customary thread to leave an external cylindrical wall and the screw shell is merely forced 20 on this end.

In the construction of the ordinary fuse, one end of the fusible link 14 is generally soldered to the center contact, as shown at 19, while an opening is formed in the body member through which 25 the other end of the fusible link is passed so that it may be soldered to the screw shell to make the necessary electric connection between the center contact and the screw shell 11. In the present lower end the lower end of the fusible link is 30 likewise soldered to the center contact 19 and to the screw shell 11, but instead of merely having a small opening in the body member 10, as is ordinarily the case, a regular pocket 20 substantially wider than the link 14 is formed which has 35 vertical side walls and which has an external opening extending vertically at least the distance between two adjacent threads. After the end of the link has been inserted in this pocket and placed in contact with the metal shell, a quantity 40 of solder is heated to a temperature higher than the melting point and is poured into the pocket, as shown at 21.

Not only does this solder secure the end of the link to the metal shell but the temperature of the 45 solder is such that a quantity of the solder flows into the thread of the shell and forms a partial but substantially arcuate thread as shown at 22. Sufficient solder adheres to the shell so as to make it utterly impossible to unscrew the shell 50 from the body member; the part of solder 21 which is formed in, fills, and rigidly held in the pocket 20, acting as an anchor. In Fig. 3, two pockets have been shown to indicate that when required a plurality of pockets may be used. 55

However, I have found that the use of one pocket formed as described above is generally sufficient.

While I have mentioned the use of solder and while I prefer to use that in connection with fuse plugs to assure a perfect electrical contact between the screw shell and the fusible link, it is evident that in many cases a hard-setting plastic material may be used with the same result, particularly, if a plurality of pockets are used.

- 10 From the foregoing it will be seen that this construction will effect a great saving in the cost of the moulds; that, in decreasing the weight of the body member, it will save material which is of great advantages in cases of "Bakelite" and similar materials; and that, inasmuch as the link 14 must be soldered to the metal shell even when the body member is provided with a thread, the pouring of the solder does not, in the case of fuse plugs, involve an additional operation.
- 15 The improved fuse plug is strong and durable in practice, and may be manufactured at low cost.
- 20 Having described the invention and its objects, what I claim as new and wish to protect by Letters Patent is:
- 25 1. An electrical fuse plug including a body portion of moldable insulating material having an interior recess and an externally smooth and cylindrical wall on the lower portion of the body, a shell whose walls are in the form of screw-threads tightly fitting said wall, a pocket formed
- 30

internally of the body and having an opening through the external cylindrical wall, the opening having a vertical extent at least equal to the distance between two screw threads, said pocket having vertical side walls, one end of fusible link 5 extending through said pocket and contacting said shell, and a solid body of solder filling said pocket and extending internally of one of said threads arcuately a sufficient distance to securely anchor said shell against removal from said body 10 member.

2. An electrical fuse plug including a body portion of moldable insulating material having an interior recess and an externally smooth and cylindrical wall on the lower portion of the body, 15 a shell whose walls are in the form of screw-threads tightly fitting said wall, a pocket formed internally of the body and having an opening through the external cylindrical wall, the opening having a vertical extent at least equal to the 20 distance between two screwthreads, said pocket having side walls, one end of a fusible link extending through said pocket and contacting said shell, and a solid body of solder filling said pocket and extending internally of one of the threads 25 arcuately for a substantial part of the circumference of the shell whereby the shell is substantially anchored on the cylindrical wall against removal therefrom.
